CAY BUHL, OF PATERSON, NEW JERSEY, ASSIGNOR TO NATIONAL TEXTILE MACHINE COMPANY, OF NORTH PATERSON, NEW JERSEY, A CORPORATION OF NEW JERSEY.

CLOTH FOLDING AND WINDING MACHINE.

1,216,280.

Specification of Letters Patent. Patented Feb. 20, 1917.

Application filed March 12, 1915. Serial No. 13,850.

To all whom it may concern:

Be it known that I, CAY BUHL, a subject of the King of Denmark, residing at Paterson, in the county of Passaic and State of New Jersey, have invented certain new and useful Improvements in Cloth Folding and Winding Machines, of which the following is a specification.

This invention relates to apparatus for folding and winding cloth and other flexible sheet material, and particularly to that class of such apparatus in which the folding is effected longitudinally of the cloth.

The object of the invention is to provide a folding and winding apparatus of the particular class indicated whereby the folding and winding operations may proceed with rapidity and under such control that in the resultant product—the roll of folded and wound material—the convolutions will have their edges all true or flush with each other.

In the accompanying drawings,

Figure 1 is a front elevation of the machine;

Fig. 2 is a side elevation;

Fig. 3 is a front elevation, with the carriage and other parts removed, the upper portion of the machine being broken away; Fig. 4 is an enlarged side elevation, partly in section, of the upper portion of the machine;

Figs. 5, 6, 7 and 8 are detail views, illustrating particularly the means for supporting the bolt or roll of wound product;

Fig. 9 is a detail view illustrating the main cloth guiding roll and the measuring means;

Fig. 10 is a rear elevation of the folding device and the cloth, together with the strip of paper which is inserted in the fold formed in the cloth;

Fig. 11 is a front elevation and Fig. 12 a rear elevation of the apex portion of said device;

Fig. 13 is a sectional plan of said device, the section being taken in a plane somewhat above its apex; and,

Fig. 14 is a similar sectional view with the cloth appearing in section.

I shall first describe the folding device and then the details of the specific apparatus herein illustrated of which it forms a part.

The folding device includes two straight-edge members *a* and *b* arranged at approximately 135° and another straight-edge member *c* intersecting the angle of the first two members at approximately 45° to the member *a*. The members *b* and *c* are in the present instance arranged in the same plane (Figs. 13 and 14), while the member *a* is arranged in a plane somewhat spaced from the first plane, a triangular distance piece *d* being interposed between the member *a* and the members *b* and *c*, the side *d'* of which distance piece bisects the angle (90°) between the members *b* *c* (Figs. 11 and 12).

In the adaptation herein shown, the member *a* extends horizontally and the cloth is led at full width downwardly and in front of the folding device as it appears in Figs. 1 and 3, being stretched around the angle formed by the members *a* and *b* and having the longitudinal line in which it is to be folded (in the present case, the center line thereof) coincident with the apex of said angle; the cloth *A* is advanced in the direction indicated by the arrows in Figs. 3 and 10, its leading end being drawn upwardly, one longitudinal half thereof being folded over on the other half to form the fold *B* (Fig. 10), which fold has one layer *B'* thereof generating at the straight-edge member *a* and the other layer *B''* thereof generating at the member *c*. The folded leading end *B* extends through the space (Figs. 13 and 14) formed between the members *a* and *c*, its folded side being in approximate contact with the side *d'* of the triangular piece *d*. Assuming the cloth to be under tension and its folded portion *B* to be drawn in the direction of the arrows in Figs. 3 and 10, the folding, generating at the apex of the angle of the device, will proceed throughout the length of the piece *A*; and so long as the direction of approach of the piece *A* is perpendicular to the member *a*, the line of fold will continue throughout the length of the piece central of its width, but if the line of approach of the piece *A* departs from perpendicular relation to the member *a* then the line of fold will shift; if such departure is to the right in Fig. 3, the line of fold will shift so that the layer *B'* will be wider than the layer *B''*, and if the departure is in the opposite direction, the line of fold will shift so that the layer *B''*

will be the wider. This is due to the fact that as A shifts to the right or left in Fig. 1 it will work up or down on the member c; when it works up the member c the width of 5 the material in the layer B' will obviously increase, and when it works down the member c such width will obviously decrease. In view of this it will be apparent that by providing means to effect relative movement 10 laterally as between the cloth and the folding device the folding line may be shifted toward the one or the other edge of the cloth; or, stated with reference to the practical advantage directly aimed at in the apparatus herein shown and described, that 15 with such means provided the operator may guide the fold in being formed along some predetermined line (for instance, the center line), causing the shifting one way or the other, according as the fold begins to depart 20 from said line. Accordingly, in the present case I mount the supply cloth roll in a carriage which the operator may move manually in the frame of the machine relatively 25 to and laterally of the folding device, which is fixed in said frame, as will now appear.

The frame of the machine comprises a base e, housings f f, tubing g having right and left hand threaded connections with the 30 base and housings f f, other brace tubings h h having similar connections with the base and said housings, super-housings i i, tubing j j having right and left hand threaded connections with the housings f f and with the 35 super-housings i i, pairs of tubes k k having conical ends seated in conical seats in the two housings and subjected to endwise pressure when the tubing j j is screwed up tight, (each set of parts f f to k k forming an up- 40 right upstanding from the base), and a brace-tube l which has threaded connection with each of the super-housings i i. The base e includes a pair of reach-rods e' e'.

The aforesaid carriage comprises upper 45 and lower T-rails m m, the upper rail running in grooves of the grooved wheels n journaled on the brackets o secured to the uprights of the frame and the lower rail being equipped with grooved rollers p running on the forward reach-rod e', pairs of bearing brackets q q and r r respectively attached to the upper and lower rails, and strips s s each connecting a bracket q with a bracket r. On the upper rail is a handle t 50 whereby the carriage may be shifted laterally by hand. The carriage affords bearings in the brackets q q for the trunnions of the roll or beam u on which the supply of cloth A to be folded and wound is wound, and in 55 the brackets r r for a guide roller v over which the cloth passes before it extends downward to be stretched around the angle formed by the members a and b of the folding device. In Figs. 1 and 9 a measuring 60 device w is shown, actuated from one of the 65

trunnions of the roller v through any suitable means x and serving to indicate the yardage folded and wound.

The take-up and winding of the folded cloth is effected as follows: A shaft y is journaled in the superhousings i i, extending through the brace-tube l, and in the superhousings it carries fixed thereon, the sprocket wheels z z; on one end it carries the fast and loose pulleys 2, 3 around which 70 the drive belt, controlled by the shifter 4, extends. Mandrels 5 and 6 are journaled in the housings f f and these carry sprocket wheels 7 within the housings and around which and sprocket wheels z chains 8 extend, the mandrel 6 being splined in its sprocket wheel 7 as shown in Fig. 4. The inner end of the mandrel 5, which is not movable lengthwise as is the case with the other mandrel, is journaled in a bracket 11 75 clamped to the brace-tube l.

Each mandrel has a flattened socketed head 9, 10 adapted to receive one end of the board 12 on which the bolt or roll of folded cloth is to be wound. When the winding 80 operation is proceeding these heads are connected by the blade 13 one end of which has a hole 14 to receive the head of a screw 15 or other projection on the mandrel head 9 and the other a longitudinal slot 16 to receive the 85 T-shaped head of a thumb-screw 16' on the mandrel head 10. The end of the blade having the hole 14 is retained in interlocked relation to said head 9 (by the head of the screw 15 being engaged in said hole) by an 90 oblique lip 17 on head 9 so long as the blade is parallel to both heads 9, 10; but the blade may be released from the screw head by tilting it to the dotted position in Fig. 8. When 95 the winding starts, the slotted end of the blade is held clamped to the head 10 by the thumb-screw, which also holds the right-hand mandrel and head 10 from withdrawing 100 from the board 12 on which the cloth is wound. When the winding is completed, 105 the thumb-screw is released, the right-hand mandrel drawn to the right to clear its head 10 from the board, the blade is disconnected from the thumb-screw, and the board and blade tilted until the latter is disconnected 110 from the screw-head 15, whereupon, board, blade and the bolt or roll of cloth being thus 115 detached, the blade may be withdrawn, to be reintroduced into the machine with a fresh (or the same) board. The slot 16' adapts the mandrels to receive boards varying in 120 length.

A beam 18 for a roll of paper 19 has its trunnions journaled on the inclined runways 20, the paper roll bearing against a guide-roller 21 journaled in fixed bearings. The strip of paper from this roll passes under the guide-roll 21 and the member a of the folding device and then up between the 125 layers B' B'' of the cloth (Fig. 10). 130

Another beam 22 for a roll of paper 23 is journaled in arms 24 projecting from the brace-tube 7, the paper strip in this case being wound with the folded material

5 wound on the board and serving to separate the convolutions thereof.

The folding device is fastened to the frame of the machine, *i. e.*, to the rigid brackets 25.

10 In operation, the drive shaft being in rotation, the board previously arranged in the heads of the mandrels is rotated and winds up the folded cloth and the paper strips, the leading ends of which may be clamped between the board and blade 13. As the winding proceeds, the folding is accomplished by the folding device in the way fully explained. The operator, by observing the folded portion of the cloth and particularly

15 20 the left-hand edges (Fig. 10) of its layers B' B'', can note whether or not the folding is proceeding true, and as soon as any departure is noted he gives the carriage movement one way or the other by means of handle *t* to correct the error. In this way the folding may be made to proceed with the nicest accuracy.

On account of the extra thickness at the fold, there is a tendency for the folded material in winding to work toward the right in Figs. 1 or 3. This I overcome, thus preserving the left-hand or folded edges of the convolutions of the wound material true or flush, by a fixed arm 26, in the present case attached to the folding device; it projects between the layers B' B'' of the material against the inside of the fold thereof.

Having thus fully described my invention, what I claim as new and desire to secure by

30 35 40 Letters Patent is:—

1. In combination, a frame, a folding device consisting of a plurality of bars arranged in angular relation to each other and in an upright plane and means to guide the cloth in an upright plane to and then around the angle formed by said bars and then back in another upright plane substantially par-

allel with the first plane, said folding device and means being movable one relatively to the other horizontally and parallel with said planes.

2. In combination, a frame, an upright carriage movable horizontally in said frame, a folding device consisting of a plurality of bars arranged in angular relation to each other and in an upright plane, a cloth beam and a guide roller arranged in the carriage at one side of and parallel with the folding device and the latter above the former, the cloth being adapted to extend from the cloth beam over the roller, then downward and around the folding device and then upward in an upright plane, and means above the folding device on which to wind the folded cloth.

3. In combination, a folding device consisting of a plurality of bars arranged in angular relation to each other, a frame in which said folding device is arranged, means to guide the cloth being folded including a carriage movable in the frame transversely of the folding device, rotary means in the frame on which to wind up the folded cloth having its axis parallel with the plane of the folding device, and a guide arm fixed in the frame and projecting in a plane substantially parallel with the folded cloth between the layers and up to the fold thereof.

4. In combination, with folding means, rotary means on which to wind the longitudinally folded material, said rotary means being spaced from the folding means, and supporting means for said folding means and rotary means, a guide arm fixed in the supporting means and projecting in a plane substantially parallel with the folded material between the layers and up to the fold thereof.

In testimony whereof I affix my signature in presence of two witnesses.

CAY BUHL.
